UNITED STATES PATENT OFFICE.

WILLIAM H. PAGE, OF NORWICH, CONNECTICUT.

AUTOMATIC BOILER-FEEDER.

SPECIFICATION forming part of Letters Patent No. 326,143, dated September 15, 1885.

Application filed October 24, 1884. (No model.)

To all whom it may concern:

Be it known that I, WILLIAM H. PAGE, a citizen of the United States, residing at Norwich, in the county of New London and State of Connecticut, have invented certain new and useful Improvements in Automatic Boiler-Feeders, of which the following is a specification, reference being had therein to the accompanying drawings.

10 My invention relates to boiler-feeders, and has for its object to automatically supply a steam-boiler with water when the water has fallen below the safety-line, and to so construct the feeding device that the several parts thereof can be readily detached when it is desired to clean the same; and the invention consists in the construction, combination, and arrangement of parts, substantially as hereinafter described and claimed.

15 In the drawings, Figure 1 is a central longitudinal section of a boiler-feeder embodying my improvements, and Figs. 2 and 3 are enlarged details of parts shown in Fig. 1.

20 Referring to the drawings, in which like letters of reference indicate like parts, A designates the main chamber of a boiler-feeder, suitably supported at a point about the height of the water-line of the boiler, and preferably cone-shaped or tapering from front to rear; 25 and B designates the float, also made tapering or cone shaped, for a purpose hereinafter described.

The main chamber is provided, at the upper and lower portions of its front, with supplemental chambers A' A'', which connect with pipes A³ A⁴, in communication with the steam and water spaces, respectively, of the boiler, to which they are connected to maintain in the chamber A the same height of water, and 30 steam-pressure to correspond, with that of the boiler. The chamber A is further provided at its front and rear with openings or apertures C C', the former of which is protected by a cover, C'', secured to the front wall of the chamber A by bolts c c, while the aperture or opening C' is closed by a plug, D, fitted therein, as shown.

The plug D is exteriorly screw-threaded, as at d, and is provided with a chamber, E, in 35 which is fitted the end of the feed-water pipe I and an inlet-aperture, G, of smaller diam-

eter than the said chamber E, and extending therefrom through the plug.

The float B is made hollow and cone-shaped or tapering from front to rear, and at its rear end is provided with a valve, F, rigidly connected thereto and hinged to the plug. The lower portion, f, of the valve is fitted between lugs d' d', formed with the plug D, and held in place by a cross-pin, e, passing through 55 the apertures in said lugs and valve. The valve F is provided with an upwardly and forwardly projecting arm, f', having a piece of rubber or other elastic material, f'', fitted in the face thereof, which is adapted to bear 60 against the inlet-aperture of the plug, as will be readily understood.

If desired, the inlet-aperture may be covered with a ring of rubber, as at h, against which the rubber block f'' of the valve is 65 adapted to fit to secure a perfectly-tight joint.

H designates a gage of any desired or suitable construction, the upper and lower arms of which communicate with the steam and water spaces of the chamber A, to indicate 75 the height of water therein.

The operation of my invention is as follows: When the water in the boiler has fallen below the safety-line, the float B in the chamber A will descend and open the valve F, allowing 80 the water from the chamber E of the plug and supply pipe I to pass through the inlet-aperture of the plug into said chamber A, and thence to the boiler through the pipe A', as will be readily understood.

85 It frequently occurs that the float will become filled with water, and be rendered thereby inoperative or its efficiency seriously impaired. To enable the float to be readily freed from water and cleaned is one of the objects 90 of my invention, and to this end I so construct the plug D as to permit of its ready disengagement from the main chamber.

When it is desired to clean the float, the feed-pipe I is detached from the plug and said 95 plug disconnected from the chamber and withdrawn therefrom until the valve is brought to view, when the pin e is withdrawn and the valve removed, thereby permitting the float to be emptied of the water contained therein 100 and cleaned. It will be observed that the cone-shaped construction of the float will per-

mit its smaller end to be drawn through the aperture C', thereby permitting the valve to be readily disconnected from the plug and the float to be quickly and easily cleaned; or, if it is desired to remove the float from the chamber A, it can be passed through the aperture C, at the front end thereof, after having been disconnected from the plug.

The supply and feed water pipes and steam-
10 pipe are provided with valves (not shown) located at suitable points, to cut off the steam and water when the float is to be cleaned.

It will be observed that my invention provides a simple, durable, and efficient automatic
15 boiler-feeder.

I am aware that it is not broadly new to provide a boiler-feeder with a float connected by arms or rods with a valve to automatically supply a boiler with water, and hence do not
20 claim such construction broadly.

Modifications in details of construction and
25 form and proportion of parts herein shown and described as an embodiment of my invention can be made without departing from the principle or sacrificing the advantages thereof—as, for instance, other means than that shown for hinging the float to the valve may be employed—and I would therefore have it understood that I hold myself at liberty to make such
30 changes and alterations as fairly fall within the scope of my invention.

Having thus fully described my invention, what I claim, and desire to secure by Letters Patent of the United States, is—

1. The combination of the cone-shaped chamber and a cone-shaped float with an outwardly-removable plug to which said float is hinged, whereby the pivotal connection between the plug and float can be exposed, substantially as shown and described.

2. The combination of the water-chamber and float with an outwardly-removable plug having an inlet-aperture to which said float is hinged, as and for the purpose set forth.

3. The combination, with the cone-shaped chamber having supplemental chambers communicating with the steam and the water pipes, said conical chamber having openings in opposite ends thereof, the larger end having a gage and the smaller end an outwardly-removable plug to which the float is hinged and to which the water-pipe is connected, as and for the purpose set forth.

In testimony whereof I affix my signature in presence of two witnesses.

WILLIAM H. PAGE.
